UNITED STATES PATENT OFFICE.

JOHN C. POETZ, OF WENATCHEE, WASHINGTON.

CLIMBING DEVICE.

1,328,251.

Specification of Letters Patent. Patented Jan. 13, 1920.

Substitute for application Serial No. 96,540, filed May 10, 1916. This application filed May 31, 1918. Serial No. 237,672.

To all whom it may concern:

Be it known that I, JOHN C. POETZ, a citizen of the United States, residing at Wenatchee, in the county of Chelan and 5 State of Washington, have invented a new and useful Improvement in Climbing Devices, of which the following is a specification.

My invention relates to improvements in 10 climbing devices, by which a person may rise or lower himself by successive steps to or from the height to which the upright to be climbed is constructed, and the objects of my invention are to provide simple and 15 efficient means, in lieu of the rungs or steps of the ordinary ladder, by which such raising and lowering may be performed, and the extent thereof determined by the operator, thereby simplifying and lightening the 20 construction of the device, making it more portable and convenient, and at the same time, enlarging the scope of its use.

I attain these objects by the mechanism illustrated in the accompanying drawings in 25 which:

Figure 1 is an elevation at A—A', and a section at B—B', Fig. 2.

Fig. 2 is a plan view of my device.

Fig. 3 is a side elevation.

30 Similar characters of reference refer to similar parts throughout the several views.

Referring to the drawing, 1 is a rod, preferably of steel and H-shaped in cross section. Mounted upon the oppositely disposed 35 flanges 2 and 2' of the rod 1 are the blocks 3 and 3', so constructed as to permit of adjustment to slide freely upon or to bind upon the rod 1 to prevent movement.

Attached transversely to blocks 3 and 3' 40 are preferably oppositely disposed foot rests 4 and 4', provided with curved projections 5 and 5', by means of which the blocks 3 and 3' are changed from a sliding or holding position to a holding or sliding 45 position. The blocks 3 and 3' are constructed so as to slide freely upon the flanges 2 and 2', in this instance in the form of a channel bar, the flanges 6 and 6' of which are wider than the thickness of the flanges 2 and 2'. To the lower ends of the flanges 50 6 and 6' rectangular lugs 7 and 7' are attached, the inner surfaces of which are spaced from the inner surfaces of the blocks 3 and 3' a distance slightly greater than 55 the thickness of the flanges 2 and 2', so

that when pressure is placed upon the foot- 60 rests 4 and 4', the upper inner edge 8 of the lug and the inner lower edge 8' of the block will bind upon the flanges and prevent the blocks 3 and 3' from sliding. It will be 65 observed that the blocks 3 and 3' are made of such a length as to slide freely upon the flanges 2 and 2'. It will be understood that the details of construction of the flanges and blocks may be changed, and still retain their 70 essential features.

The operation of my climbing device is 75 very simple. The weight of the foot-rests 4 and 4' alone is sufficient to hold the blocks 3 and 3' at any point upon the rod 1, and the greater the weight placed upon the foot- 80 rests 4 and 4' the more firmly the blocks 3 and 3' are bound upon the flanges 2 and 2'. A person using my device steps upon the 85 foot-rests 4 and 4', and raises one foot upward and inward against the guard 5 or 5', thereby bringing the inner surface of the blocks 3 or 3' parallel with the surface of the flanges 2 or 2', releasing the binding edges 8 and 8' and permitting of the block 90 being moved upward or downward on the flange. The other block is then similarly 95 released and moved upward or downward, and so on. By the use of the double sliding track, the feet may be moved past each 100 other without restraint, as is usual in ordinary climbing.

Having thus described my invention, what I claim is:—

1. A climbing device of the character described comprising in combination an H-shaped rod in cross-section, channel blocks mounted upon the flanges of said H-shaped rod for permitting of adjustment to slide freely and bind upon said rod, foot rests 95 transversely attached to said blocks, curved projections on said foot rests allowing a changing of the blocks from a sliding or a binding position or vice versa, and rectangular lugs adjacent the lower end of the 100 flanges of the blocks, having their inner surfaces spaced from the inner surfaces of said blocks for a distance slightly greater than the thickness of said H-shaped rod flanges, said lugs and blocks binding with 105 their inner edges upon the flanges of the H-shaped rod if pressure is exerted on said foot rests for preventing the blocks from sliding.

2. In combination with a rod of H-section, 110

of foot supporting means including a pair of channel blocks straddling the opposite flanges of the rod, each block having a pair of opposing lugs extending inwardly from its lower edge and across the inner face of the supporting flange toward the web of the rod, the sides of one channel block having their upright edges formed on a bias so as to diverge upwardly relative to the opposing edges of the companion block.

3. In combination with a rod of H-section, of foot supporting means including a channel block straddling one flange of the rod and having opposing lugs extending inwardly over the inner face of said flange toward the web of the rod, said lugs being disposed adjacent the lower edge of the channel block, the latter extending up along

side the outer face and edges of the flange above the lugs to guide the channel block. 20

4. In combination with a rod of H-section, of foot supporting means including a pair of channel blocks straddling the opposite flanges of the rod, each block having a pair of opposing lugs extending inwardly from its lower edge and across the inner face of the supporting flange toward the web of the rod, outwardly extending brackets secured to the lower portions of the blocks, foot rests secured to the brackets, and means 25 located on the inner side of each foot rest beneath which the foot is engageable.

JOHN C. POETZ.
